(57) **CLAIM**

The ornamental design for a taper jig, as shown and described.

DESCRIPTION

FIG. 1 is a front, top, right side isometric perspective view of a taper jig in accordance with my design.

FIG. 2 is a front elevation view of the taper jig shown in FIG. 1.

FIG. 3 is a rear elevation view of the taper jig shown in FIG. 1.

FIG. 4 is a left elevation view of the taper jig shown in FIG. 1.

FIG. 5 is a right elevation view of the taper jig shown in FIG. 1.

FIG. 6 is a top plan view of the taper jig shown in FIG. 1.

FIG. 7 is a bottom plan view of the taper jig shown in FIG. 1.

FIG. 8 is an enlarged partial top plan view of the taper jig highlighted in FIG. 6; and,

FIG. 9 is an enlarged partial top plan view of the taper jig highlighted in FIG. 6.

The broken lines show portions of a taper jig which form no part of the claimed design.

The “dash-dot” broken lines seen in FIGS. 6, 8, and 9, are for the purpose of showing an enlarged portion of the claimed design, and form no part thereof.
